CLAIM

We claim the ornamental design for a kettle, as shown and described.

DESCRIPTION

FIG. 1 is a front perspective view of a kettle of the present disclosure;

FIG. 2 is a rear perspective view of the kettle of FIG. 1;
FIG. 3 is a front elevational view of the kettle of FIG. 1;
FIG. 4 is a rear elevational view of the kettle of FIG. 1;
FIG. 5 is a first side elevational view of the kettle of FIG. 1;
FIG. 6 is a second side elevational view of the kettle of FIG. 1; and

FIG. 7 is a top plan view of the kettle of FIG. 1; and,
FIG. 8 is a bottom plan view of the kettle of FIG. 1.
The broken lines in the drawing views represent unclaimed
portions of a kettle, which are included for the purpose of
illustrating unclaimed environment only, and forms no part
of the claimed design.

1 Claim, 8 Drawing Sheets
